02-823
01406

AU
OP

EX
D 003,997

en Taylor's
"Czarina."

3997

PATENTED APR 26 1870

Fig. 1.

Fig. 2.

Witnesses
John R. Wright
George E. Buckley

Inventress
Gostling, atty for
Anna Ellen Taylor

United States Patent Office.

ANNIE ELLEN TAYLOR, OF PHILADELPHIA, PENNSYLVANIA, ASSIGNOR TO HARRY TAYLOR, OF SAME PLACE.

Design No. 3,997, dated April 26, 1870.

DESIGN FOR A SHAWL-MANTLE.

The Schedule referred to in these Letters Patent and making part of the same.

To all whom it may concern:

Be it known that I, ANNIE ELLEN TAYLOR, of the city of Philadelphia, in the State of Pennsylvania, have invented and produced a new and original Design for a "Czarina;" and I do hereby declare the following to be a specification thereof, reference being had to the annexed drawing, in which—

Figure 1 represents my design as it appears on the wearer, and

Figure 2 represents the same, unfolded.

My design relates to a garment, called a "Czarina," of such shape and configuration as to have the appearance of a mantle in front and of a shawl at the back.

To produce a "Czarina" made according to my design, a strip is first cut from one of the long sides of a rectangular piece of goods, of which strip the collar and trimmings are made, as hereinafter described.

The rectangular piece is then folded double, lengthwise, and cut "bias" near the middle, so as to divide it into three pieces, the middle piece being of triangular shape.

The two end pieces A and B, of the same size and shape, are sewed together, as shown, and the middle piece having been cut lengthwise, so as to divide it into halves of triangular shape, these halves C and D are each doubled lengthwise, placed with their long edges in contact, and sewed together on the seam E F, forming an ornament of triangular shape, with the apex at or near the lowest point of the back, as shown.

The strip which was first cut from the goods is now cut "bias" into three pieces, two of which, G and H, are of equal length, and are sewed to the neck of the "Czarina," to form a collar.

The other piece is cut lengthwise into two or more parts, which are each gathered into a fan-shape, and sewed over the triangular ornament, as shown at I and K.

Having thus described my invention,

What I claim as new, and desire to secure by Letters Patent of the United States, is—

The design for a "Czarina" or "shawl-mantle," as shown.

ANNIE ELLEN TAYLOR.

Witnesses:

JAMES I. ALLISON,
JOHN FIELD.